DESIGN FOR A LIBRARY TRUCK

Eliot R. Scudder, Braintree, Mass., assignor to
Jarvis & Jarvis, Inc., Palmer, Mass., a corpo-
ration of Massachusetts

Application January 24, 1939, Serial No. 82,552

Term of patent 14 years

To all whom it may concern:

Be it known that I, Eliot R. Scudder, a citizen of the United States residing at Braintree, in the county of Norfolk and State of Massachusetts, have invented a new, original, and ornamental Design for a Library Truck, of which the following is a specification, reference being had to the accompanying drawing, forming a part thereof.

The figure is a perspective view of a library truck, embodying my new design. It will be un-

derstood that the library truck of said design presents the same appearance when viewed from either the right or left side thereof, and the view shown in the drawing may be considered as taken from the front and left side.

I claim:

The ornamental design for a library truck, as shown and described.

ELIOT R. SCUDDER.
